UNITED STATES PATENT OFFICE.

EUGÈNE SCHNEIDER, OF LE CREUZOT, FRANCE.

PERCUSSION-FUSE.

1,152,917.

Specification of Letters Patent.

Patented Sept. 7, 1915.

Application filed July 31, 1914. Serial No. 854,272.

To all whom it may concern:

Be it known that I, EUGÈNE SCHNEIDER, of Le Creuzot, France, have invented new and useful Improvements in or Relating to Percussion-Fuses, which is fully set forth in the following specification.

This invention relates to percussion fuses and has for its object to provide a percussion fuse such that it does not act until after the projectile has passed through the obstacle that it encounters, no matter what the thickness of this obstacle may be. A projectile provided with this improved fuse will only burst behind the obstacle whether the latter be a gun screen, a wall, a ship's plate or armor plate. Similarly the projectile will only burst beyond the target, whether the latter be attacked directly or after passage through a resisting medium such as water.

According to this invention, the fuse comprises a striker holder and a priming holder, both movable in the forward direction under the influence of the impact of the projectile with an obstacle, one of the elements being held in the displaced position, while the other is free and bears against the front end of the body of the fuse by its inertia during the retardation of the projectile, this being the condition so long as this retardation continues; the movement for firing takes place after the obstacle has been penetrated, under the influence of a spring which has been compressed by the forward movement of the element.

In order that the said invention may be clearly understood and readily carried into effect, the same will now be described more fully with reference to the accompanying drawings, in which:—

Figures 1 and 2 illustrate the fuse in sectional elevation, the parts being in two different positions. Fig. 3 is a sectional plan on the line 3—3 in Fig. 1. Fig. 4 illustrates a modification, the two halves of the figure showing the parts in two different positions.

The two usual elements, that is to say, the striker holder B and the priming holder C are arranged in the fuse body A. In accordance with the invention each of the two elements B and C is movable and they are arranged in such a manner as to move in the same direction under the influence of the shock of the projectile against an obstacle. With this object, the element B normally bears against the rear end a of the fuse body,

while the other element C is normally held against an intermediate partition a² in the said fuse body by a counter spring c, which bears against the front end a' of the fuse body.

The element B is provided with a device which upon the simultaneous displacement of the two elements B and C insures that it shall stop and remain in the displaced position. For stopping it, the body B of the striker holder carries projections or a continuous collar b which strikes against the lower face of the partition a² (Fig. 2). Normally segments b' embrace a split extensible ring b² which by the thrust of its two extremities tends to separate them (Fig. 3). A safety device of any known kind which may, for example, be constituted by segments D united by a spring d prevents accidental displacement of the element B during transportation. So long as the segments D occupy the position shown in Fig. 1, the collar b bearing against their lower face prevents any forward movement of the part B. On firing, the safety device becomes inoperative, the segments D separating under the influence of centrifugal force, and assuming the position indicated in Fig. 2. The elements B and C retain their normal position in the fuse body A and only leave this position when the projectile strikes an obstacle. As soon as an obstacle is encountered, the two elements move one in front of the other in the fuse body, and it is only necessary to make these elements of appropriate mass to insure that, notwithstanding the compression work of the spring c, the element C immediately becomes accelerated relatively to the element B. This element B is stopped in its forward movement as soon as the collar b strikes against the partition a² (Fig. 2). Furthermore when the lower edge of the segments b' has passed beyond the shoulder a³ of the fuse body, the said segments separate under the influence of the spring b² and of centrifugal force thus locking the element B in its cocked position. The element C has previously struck against the front end a' of the fuse body. The retarding action that the obstacle struck by the projectile exerts upon the velocity of the latter constitutes an actual counter-acceleration, the effects of which upon the various elements in movement are proportionate to their masses. It follows that the retarding effort exerted

is 85

upon the projectile and the fuse body is appreciably greater than that exerted upon the element C so that the latter remains hard against the end of the fuse body. When the 5 retarding effort ceases or is suddenly reduced, which is what occurs when the projectile has passed right through the obstacle, no appreciable effort tends to maintain the element C against the end a' and any effort 10 that might occur would in any case be insufficient to overcome the counter action of the spring c . Under this action the element C is moved rearward, and firing takes place when the two elements C and B encounter 15 each other.

In the example illustrated, the lower element B carries the striker and the upper element carries the primer; it will however be understood that the reverse arrangement 20 might equally well be adopted.

In certain cases, it may be advantageous to slightly retard the action of the counter spring, while at the same time giving it sufficient tension to produce a vigorous shock 25 between the elements B and C for the purpose of firing. With this object it is only necessary to provide the element C with locking members such, for example, as those indicated in the modification represented in 30 Figs. 4 and 5. In the thickness of the element C radiating bolts E are housed and at the moment at which the element strikes the upper end a' of the fuse body, these bolts engage in an annular groove a^* formed in 35 the fuse body A. The rear end of this groove is chamfered and forms a support for a corresponding chamfer on the bolts E. So long as the difference between the retarding efforts acting respectively upon the projectile and upon the element C is sufficiently 40 great to prevent the spring c from overcoming this pressure plus the resistance opposed by the bolts E to being pressed aside, the element C will remain pressed against the 45 end of the fuse body. This method of locking in which the action of the spring c is retarded can be modified in any desired manner.

The fuse described can be constructed as 50 a head fuse and it may or may not comprise the additional locking device that has just been described.

It should be noted that in the examples described a partition a^2 forms by means of 55 its lower face a stop for retaining the element B while by its upper face it forms a

support for the element C normally and during firing. This simple device is not the only one that may be employed, however. The two elements B and C might normally 60 be maintained apart at a suitable distance by various means; it is sufficient if these means permit of the release of the two elements when the projectile is fired.

What I claim and desire to secure by Letters Patent of the United States is:—

1. A percussion fuse for projectiles intended to burst after passing through a target, comprising a strike element and a priming element both movable in a forward direction on impact of the projectile, means for holding one element out of contact with the other element after impact, and resilient means acting on the other element and rendered active after the projectile passes 75 through the target for moving said element into firing contact with its companion element.

2. A percussion fuse for projectiles intended to burst after passing through a target, comprising a strike element and a priming element, means normally holding one element in safety position for handling, both elements movable in a forward direction on impact of the projectile, means for holding 80 one element out of contact with the other element after impact, and resilient means acting on the other element and rendered active after the projectile passes through the target for moving said element into firing 85 contact with its companion element.

3. A percussion fuse for projectiles intended to burst after passing through a target, comprising a strike element and a priming element both movable in a forward direction on impact of the projectile, means for holding one element out of contact with the other element after impact, resilient means acting on the other element and rendered active after the projectile passes 95 through the target for moving said element into firing contact with its companion element, and means for retarding the action of 100 said spring.

In testimony whereof I have signed this specification in the presence of two subscribing witnesses.

EUGÈNE SCHNEIDER.
